AUTOMATIC ELECTRICALLY-ACTUATED TRAIN-CONTROLLING SYSTEM.

1,187,660.

Specification of Letters Patent. Patented Apr. 27, 1915.

Application filed July 9, 1903. Serial No. 506,850.

To all whom it may concern:

Be it known that I, EDWARD L. ORCUTT, a citizen of the United States, and a resident of Somerville, in the county of Middlesex and State of Massachusetts, have invented a new and useful Improvement in Automatic Electrically-Actuated Train-Controlling Systems, of which the following is a specification.

The present invention which is an improvement on my U. S. Letters Patent No. 531,914, dated Dec. 18, 1894, relates to automatic electrically-actuated train-controlling systems and its object is to provide a closed-circuit system for automatically governing a train by apparatus and circuits carried by the locomotive and coöperating with apparatus and circuits on the road-bed.

The drawings which accompany and form a part of this specification illustrate several forms of apparatus and circuit arrangements whereby my invention may be carried into effect; but it will be understood that both the apparatus and circuit arrangements may be subjected to a wide range of variation without departing from the principle of my invention.

In the drawings—Figure 1 is a diagram of a locomotive provided with one form of apparatus and circuits arranged in accordance with my invention. Fig. 2 is a diagram representing one form of apparatus and circuits carried by the road-bed. Fig. 3 is a diagram illustrating a modification of the locomotive and track apparatus and circuits. Fig. 4 is a diagram of another modification of the locomotive and track apparatus and circuits. Fig. 5 is a diagram of still another modification of the locomotive and track apparatus and circuits. Fig. 6 is a diagram of another modification of the track circuits.

In the particular drawings selected for more fully disclosing my invention, 5 represents a suitable generator of direct current, such for example as a dynamo, which may be mounted on the shaft 41 of the turbine 42 supplied with steam through a pipe provided with a valve 43 and which has an exhaust pipe 44.

The source of electrical energy 5 hereinafter referred to as the generator, although of course it will be understood that in lieu of a dynamo-electric machine a primary or

secondary battery may be employed, is connected in Fig. 1 with three circuits.

The first circuit which is an open circuit is termed the track-circuit charging-circuit and consists of the conductor 8 connected to the pole 4, the contact-maker or looping brush 9, arranged to contact at intervals with the contact plate or rail 1', and the conductor 6 connected to the pole 3 and with the continuous rail 2 through the brush 7 or the metallic portions of the locomotive 5 and the wheels thereof.

The second circuit which is a closed circuit is termed the actuating-circuit charging-circuit *i. e.* a circuit for charging or energizing the actuating circuit and consists of the conductor 8 connected to said pole 4, conductors 10 and 11, the electromagnets 12, 13 connected in parallel, the conductor 14, the contact-maker or looping brush 15, arranged to contact at intervals with the contact plate or rail 2', the stop 16 with which said brush normally is held in contact by the spring 17, the conductor 18, resistance 20, conductor 19 and pole 3.

The third circuit which is a closed circuit is termed the train-controlling circuit and consists of the pole 4, conductors 8 and 10, the electromagnets 25, 26, 27 in multiple, the conductor 24, the safety signal herein shown as the lamp 28, conductor 29, front stop 30 of the armature 31 of the magnet 13, conductor 32, back stop 33 of the armature 34 of the magnet 12, conductor 19 and pole 3 of the generator.

The armature 31 of the magnet 13 is held against its front stop 30 when the actuating-circuit charging-circuit is closed, and the armature 34 is held against its back stop 33 by the spring 36 when said circuit is closed, and the magnet 12 is normally energized, said spring being so adjusted as to overcome the normal attraction of said magnet on its armature. The normal energization of the magnet 12 is governed by the resistance 20 included within the actuating-circuit charging-circuit and when the energization of the magnet 12 is abnormally increased, as by a short circuit, the tension of the spring 36 is overcome and the armature 34 is drawn against its front stop 37 thereby breaking the train-controlling circuit. When the actuating-circuit charging-circuit is opened, the armature 31 of the magnet 13 is drawn

against its back stop 38 by the spring 35 thereby opening the train-controlling circuit. Thus it will be seen that either by an increase or decrease of the current strength 5 in the actuating-circuit charging-circuit which includes the magnets 12, 13, resistance 20 and looping-brush 15, the train-controlling circuit will be opened.

The electromagnets 25, 26, 27 are provided 10 with armatures 25', 26', 27' respectively, carrying connecting rods which in a manner now well understood by those skilled in the art control, the operation of the air brake, the motive fluid operating the locomotive 15 and the track-sanding apparatus respectively. While in Fig. 1 I have shown three separate magnets for this purpose, in the modification illustrated in Fig. 3 one magnet 25' may be employed to accomplish all 20 three results.

The front stop 37 of the armature 34 is connected by conductor 39 with one terminal of a signal apparatus herein shown as the danger lamp 40, the other terminal of which 25 is connected by conductors 24, 10, and 8 to the pole 4. The back stop 38 of the magnet 13 is also connected by the conductor 39 to one terminal of said danger lamp. Normally when the train-controlling circuit is 30 closed the safety signal is energized. Under abnormal conditions when the train-controlling circuit is opened and the armature 31 is drawn against the back contact 38, or when it is over-energized and the armature 34 is 35 attracted to the front stop 37, the safety signal device is deenergized and the danger signal device is actuated.

It will of course be understood that mechanical devices such as semaphores may be 40 employed in lieu of the safety lamp 28 and the danger lamp 40 herein shown, and also that these signal devices may be entirely omitted.

The locomotive circuits and apparatus 45 operate with the track-circuits and apparatus shown in Figs. 2 to 6 inclusive. In these figures, 2 represents one of the rails of the track hereinafter referred to as the continuous rail, the several portions thereof being 50 electrically connected, and the opposite rail hereinafter referred to as the sectional rail is formed of a series of insulated sections 1. In Figs. 2, 3 and 4 each of said sections 1 is in electrical contact with the 55 contact plates 1' by means of conductors 62 each of which includes a resistance 63 which may be an inductive resistance. The contact plates 1' preferably are located close to the rail of the section preceding the one with 60 which they are connected. The opposite end of each sectional rail 1 to which the contact plate 1' is connected is in electrical connection with the continuous rail 2 by the conductor 64 which includes the electromagnet 65 73. The open circuit formed by the contact

plate 1' (or the series of contact plates 1', 1', as shown in Fig. 2), resistance 63, conductor 62, electromagnet 73 and continuous rail 2 is termed the track-circuit. A contact plate 2' preferably shorter than the contact plate 70 1' is arranged near each contact plate 1' and in Figs. 2 and 3 is connected by conductor 69 with the front stop 65 of the magnet 73 through a resistance 67 and is directly connected with the back stop 68. The armature 70 is normally held against the back stop 68 by the spring 71 and is connected by conductor 72 to the continuous rail. The open circuit which includes the contact plate 2' and stops 65 or 68, as the case may be, the armature 71, conductor 72 and continuous rail is termed the actuating-circuit. When the electromagnet 73 is energized the armature 70 makes contact with the front stop 65 and the resistance 67 thereby is included in the actuating-circuit. As shown in Fig. 2, two or 75 more contact plates 2', 2', electrically connected may be employed.

The operation of the locomotive apparatus shown in Fig. 1 with the track apparatus shown in Fig. 3 is as follows:—The looping-brush 9 of the locomotive advancing from left to right comes in contact with the plate 1' whereupon the open track-circuit charging-circuit and the open track-circuit 80 above referred to coöperate to form a single closed circuit traced as follows: pole 4, conductor 8, brush 9, contact plate 1', resistance 63, conductor 62, sectional rail 1, electromagnet 73, conductor 64, continuous rail 100 2, brush 7 (or wheel and metallic parts of locomotive) conductor 6 and pole 3. The armature 70 is attracted and makes contact with the front stop 65, thereby cutting the resistance 67 into the actuating-circuit. 105 Shortly after brush 9 makes contact with plate 1', brush 15 strikes contact plate 2' thereby opening the normally closed actuating-circuit charging-circuit between the stop 16 and the brush 15, cutting the resistance 20 out of said circuit and causing the now open actuating-circuit charging-circuit to coöperate with or to be looped into the actuating-circuit and form a closed circuit traced as follows:—pole 4, conductors 8, 10 110 and 11, magnets 12, 13, conductor 14, looping-brush 15, contact plate 2', conductor 69, resistance 67, front stop 65, armature 70, conductor 72, continuous rail 2, brush 7 (or locomotive wheel), conductor 6 and pole 3. 115 Thus inasmuch as the resistances 20 and 67 are approximately equal, the actuating-circuit charging-circuit on the locomotive remains in its normal energized condition and there is no change in the relative positions of 120 the apparatus carried by the locomotive. However, a train or metallic obstruction on the track would cause a short circuit between the sectional rail 1 and the continuous rail 2 so that the magnet 73 would not 125 130

be energized and its armature 70 would remain against its back stop 68. The resistance of the circuit formed by the actuating-circuit charging-circuit on the locomotive 3 and the actuating-circuit on the road-bed being reduced by the cutting out of the resistance 20 as above set forth, without the cutting in of the equivalent resistance 67, the strength of the current in this circuit will be increased, thereby enabling the magnet 12 to draw the armature 34 from its back stop 33 to its front stop 37. The resulting opening of the train-controlling circuit between the back stop 33 and the armature 34 causes the deenergization of the electromagnets 25, 26, 27, the operation of the mechanism controlled by their respective armatures, the deenergization of the safety signal-indicating device 28 and the energization of the danger signal-indicating device 40.

The operation of the locomotive apparatus shown in Fig. 1 in connection with the track apparatus shown in Fig. 2 is identical with that above described with the exception that the train after arriving at the first set of contact plates 1', 2', and receiving an indication of danger and having been brought to a standstill, upon proceeding farther would come upon the second set of contact plates to duplicate the testing of the mechanism. The apparatus shown in Fig. 1 will also operate in connection with the track apparatus shown in Fig. 4, in a manner that will be obvious.

In Fig. 3 the track-circuit charging-circuit is traced from pole 4 by conductor 8 to brush 9 and from brush 3 by conductor 6 to brush 7 or the locomotive wheels to the continuous rail 2. The actuating-circuit charging-circuit is traced from pole 4, conductors 8 and 10 to electromagnet 12', thence by conductor 14 to looping-brush 15, back stop 16, resistance 20, conductor 18 and thence back to pole 3 by conductor 6. This circuit is maintained closed at the contact 16 by the spring 17.

The train-controlling circuit is traced from brush 4, conductor 8 to the safety signal-indicating device which may be the lamp 28 and electromagnet 25''' provided with the armature and connecting rod 25''', said lamp and magnet being connected in parallel, thence to the spring C mounted upon the support A, and from spring C to spring D mounted upon the support B, and thence by contact point G to the armature 34', thence by conductor 19 to pole 3. The stop F arranged to coöperate with the spring D is connected by the conductor E' to the stop E arranged to coöperate with the armature 34', and thence by conductor 39 to the danger signal-indicating device 40 which in turn is connected to conductor 8. The connecting rod 25''' is employed to operate the

air brakes, control the motive fluid or operate the sanding mechanism jointly or separately as may be desired.

The current normally flowing in the actuating-circuit charging-circuit which includes the magnet 12' is so regulated by the resistance 20 that the armature 34' is attracted in opposition to its spring 36' and the spring D so that it breaks contact with the stop E but does not draw the spring D 70 out of contact with spring C or cause said spring D to make contact with the stop F. Should the energization of the magnet 12' be so increased that spring D is forced in contact with stop F and out of contact with 80 spring C, the train-controlling circuit would be opened between C and D, the safety lamp 28 would be extinguished, the danger signal lamp 40 lighted by the closure of its circuit between the spring D and the contact F, and the armature 25''' perform its function of bringing the train to a standstill. Should magnet 12' become deenergized, so that the spring 36' would draw the armature 34' against the back stop E, the armature would 90 break its contact with the spring D thereby opening the train-controlling circuit at this point with the same results as above described.

The operation of the locomotive apparatus shown in Fig. 3 in connection with the track apparatus shown therein will be obvious in view of the foregoing description of the operation of the locomotive apparatus shown in Fig. 1 in connection with the 100 track apparatus of Fig. 3.

In that modification of my invention shown in Fig. 4 I have shown two additional electromagnets 45, 46 whose armatures are included in the train-controlling circuit for the purpose of opening the train-controlling circuit in case any of the locomotive circuits become injured or short-circuited. In Fig. 4 the track-circuit charging-circuit is traced from brush 4, conductors 8, 24 and 53 to electromagnets 45, 46 connected in parallel, thence by conductor 80 to the looping-brush 9, back stop 81, against which said brush is held by spring 17, resistance 82 and thence by conductor 19 to pole 3. The actuating-circuit charging-circuit is the same as that above traced in connection with Fig. 1. The train-controlling circuit in addition to the apparatus described in connection with Fig. 1 includes the front 110 stop 49 and armature 48 of the magnet 46, normally held against said stop 49, conductor 57 and back stop 50 and armature 47 of the electromagnet 45 normally held against said stop 50. The opening of the track-circuit charging-circuit will cause the armature 48 to leave its front stop 49 and to make contact with its back stop 52 thereby 115 opening the train-controlling circuit at 49 and closing the circuit of the danger signal 120 125 130 135

lamp 40 by way of the conductor 59. Should the strength of the current in the track-circuit charging-circuit be increased beyond its normal value as governed by the resistance 82, the armature 47 of the magnet 45 will be attracted to its front stop 51 thereby opening the train-controlling circuit at 50 and closing the circuit of the danger signal lamp 40 at the front stop 51. Thus it 10 will be seen that by the over-energization or under-energization of the track-circuit charging-circuit, the train-controlling circuit will be opened and the mechanism controlled by the magnets 25, 26, 27 operated. 15 The operation of the system shown in Fig. 4 will be obvious from the foregoing description of the operation of the system shown in Fig. 1. A short circuit between the rails 1 and 2 and the consequent deenergization 20 of the magnet 73 causing its armature 70 to fall against the back stop 68' will open the circuit formed by the actuating-circuit charging-circuit on the locomotive and the actuating-circuit on the road-bed at the contact 25 65 thereby deenergizing the magnet 13 and opening the train-controlling circuit. It will be understood of course that the locomotive apparatus shown in Fig. 4 may be employed in connection with the road-bed 30 circuits shown in Figs. 2 and 3.

In Fig. 5 the track-circuit charging-circuit is omitted and the track-circuit which in this case is a closed circuit is energized from the source 74 connected as shown between the continuous rail 2, sectional rail 35 1 and magnet 73. The other circuits are identical with those described in Fig. 1.

In the modification of the road-bed system shown in Fig. 6 the circuits are so arranged that the actuating-circuit charging-circuit supplies the track circuit with sufficient energy to energize the magnet 73, a suitable resistance being interposed between the sectional rail 1 and the contact plate 2'. 40 45 The operation of the several forms of locomotive apparatus in connection with the road-bed apparatus shown in Fig. 6 is the same as that above set forth. The arrangement shown in Fig. 6 does not require the contact plate 1' with its cooperating brush and the track-circuit charging-circuit, and 50 also obviates the necessity of employing

separate sources of electric energy upon the road-bed. This arrangement for charging the track-circuit from the actuating-circuit 55 charging-circuit would necessitate a slight change in the value of the resistance 20 in the normally closed actuating-circuit charging-circuit on the locomotive in order that the proper current strength in the several circuits 60 may be suitably adjusted.

I claim:

1. In a train-controlling system, an open track circuit, an open actuating circuit, a track-circuit charging-circuit arranged to be looped into said track circuit, an actuating-circuit charging-circuit arranged to be looped into said actuating circuit, a closed train-controlling circuit, means operated by the over-energization of said actuating-circuit 70 charging-circuit for opening said train-controlling circuit, and means associated with said track circuit for controlling said actuating circuit.

2. In a train-controlling system, an open track circuit, an open actuating circuit, a track-circuit charging-circuit arranged to be looped into said track circuit, an actuating-circuit charging-circuit arranged to be looped into said actuating circuit, a closed 75 train-controlling circuit, means operated by the over-energization of said actuating-circuit 80 charging-circuit for opening said train-controlling circuit, and means associated with said track circuit for varying the resistance of said actuating circuit.

3. In a train-controlling system, an open track-circuit, an open actuating-circuit, a track-circuit charging-circuit arranged to be looped into said track-circuit, an actuating-circuit charging-circuit arranged to be looped into said actuating-circuit, a closed 90 train-controlling-circuit, means operated by the over-energization of said track-circuit 95 charging-circuit for opening said train-controlling-circuit, and means associated with said track-circuit for controlling said actuating-circuit.

In testimony whereof I have affixed my signature, in presence of two witnesses.

EDWARD L. ORCUTT.
